UNITED STATES PATENT OFFICE.

DOMENICO DI LEONARDO, OF ELLWOOD CITY, PENNSYLVANIA.

ENGINE-STARTING DEVICE.

1,120,922.

Specification of Letters Patent. Patented Dec. 15, 1914.

Application filed September 27, 1912. Serial No. 722,610.

To all whom it may concern:

Be it known that I, DOMENICO DI LEONARDO, a citizen of the United States, residing at Ellwood City, in the county of Lawrence 5 and State of Pennsylvania, have invented new and useful Improvements in Engine-Starting Devices, of which the following is a specification.

My invention relates to a starter device 10 for internal combustion engines.

One object of the invention is to provide an improved form of means for starting the engine, which means operates in combination with the main shaft of the engine or an 15 extension thereof provided with a spiral groove.

Another object of the invention, and in connection with said mentioned object, is to provide means which may be thrown into 20 or out of operative relation with the groove referred to.

Another object of the invention in connection with said mentioned objects, is to provide means whereby a movable device may 25 be operated after the projection of the means into the groove referred to, so as to cause rotation or turning over of the engine shaft.

A further object of the invention is to 30 generally improve the construction of a starter of this type.

Further objects of the invention, mostly minor in nature, will appear from the description following taken in connection with 35 the drawings accompanying this application, wherein the preferred embodiment is shown.

In said drawings:—Figure 1 is a side view but with the guide rails mostly broken 40 away; Fig. 2 is a plan view; Fig. 3 is an end view; Fig. 4 is a view partly in elevation and partly in section, illustrating the pin means for engaging the spiral groove of the rod or the extension of the engine shaft; 45 Fig. 5 is a detail view illustrating the rod or extension of the main shaft showing one of the pins in the groove thereof, and; Fig. 6 is a detail view illustrating part of the pin operating means.

Like reference characters designate like 50 parts throughout the several views of the drawings.

Referring specifically to the drawings, 1 55 designates suitable guide rails provided with grooves 2 in which are mounted wings 3 of a slidable shaft-actuating body 4. Said

body 4 has secured thereto upper and lower frames 5 which are secured in place by means of bolts 6 passing through lugs 7 thereof and through the wings 3. 60

Numerals 8 designates the main shaft of an internal combustion engine, and 9 designates an extension shaft which is fastened to rotate with the shaft 8, and which may be formed integral or of the same piece therewith, if 65 desired. The shaft 9 extends loosely through a central opening in the body 4. Said shaft 9 as shown, is provided with a spiral groove 10 which in effect, converts the shaft into a screw rod. 70

Suitably mounted in cross arms 11 of the frames 5, are shafts 12, which shafts at their inner ends are provided with screw threads at 13 and extend into openings 14 of the body 4 so that the threads will engage screw 75 threads provided in said openings. On each shaft 12 is provided a pinion or gear wheel 15. In the cross arms 11 are also slidably mounted, shafts 16 which are provided with screw threads at 17 and which shafts extend into an opening 18 in the body 4, and engage screw threads provided therein. Said shafts 16 have mounted thereon pinion or gear wheels 19 adapted to mesh with the 80 pinion or gear wheels 15. 85

Numeral 20 designates a rod which is fastened in a suitable manner in the body 4, and at one end is provided with screw threads engaged by a nut 21. At its other end the rod 20 is provided with a stop arm 90 designated 22. On the rod 20 is adapted to slide a cross head 23 which is provided with an opening through which said rod 20 extends. At each end of the cross head 23 is pivoted as at 24, pitmen 25 which in turn 95 are pivoted at 26 to crank arms 27 rigidly fastened on the shafts 16. To the cross head 23 is pivoted at 28 a yoke 29, into an elongated slot 30 of which, provided by the arms of the yoke, extends and moves the stop 100 arm 22.

To the body 4 is fastened a main actuating rod 31, which may have a reduced shank 32 passing through the body and beyond which body it is provided with screw threads 105 adapted to be engaged by a nut 33. To the rod 31 at 34, is pivoted a link 35 which link 35 in turn, is pivoted at 36 to a main operating lever 37. Said lever 37 is pivoted at 38 to a suitable part such as 39 which may 110 be a portion of the frame or chassis of an automobile or self-propelled vehicle. If de-

sired, any suitable means may be employed to lock or secure the lever 37 against accidental movement.

To the lever 37 are secured brackets 40 in which is turnably mounted a rod 41 having a crank arm 42, to which is pivoted at 43 a link 44. Said link 44 is pivoted at 45 to a connecting rod 46 secured or connected in any suitable manner to the yoke 29. On 10 the lever 37 is fastened a toothed segmental rack 47 adapted to be engaged by suitable means located adjacent a hand-engaging member 48 on the rod 41 for the purpose of fastening or locking the rod in such position as to prevent accidental movement thereof. Such means engaging the rack may be a tooth such as 49, preferably made of spring metal and fastened to the rod 41 or hand member 48.

20 In operation, in order to turn or rotate the engine shaft in order to start the engine, the rod 41 by means of manual engagement with the member 48, is turned so as to turn the shafts 16 and accordingly the gear wheels 19 through the medium of the crank arm 42, link 44, rod 46, yoke 29, pitmen 25 and crank arms 27. Upon the shafts 16 and gear wheels 19 being rotated, the threads 17 25 engage the appropriate threads of the body 4 in the opening 18, which causes the shafts to move the gears laterally with respect to 30 the body. The gears 19 in turning, turn the gears 15 which in turn rotate the shafts 12 and cause the same to slide or move laterally with respect to the body and to the 35 same extent as do the shafts 16. By thus sliding or moving the shafts 12 the same may be brought into such position that the inner ends thereof will enter or engage the 40 spiral groove 10 of the extension shaft 9. The direction of the screw threads of the several shafts 12 and 16 are of course, such as to enable the movement described to be had. After the shafts 12 have been thrown 45 or moved into the groove 10, the operating lever 37 is moved so that the body 4 will slide along the shaft 10, being guided in the rails 1 by means of the wings 3. During 50 such sliding movement of the body 4, the shafts 12 will act against the walls of the extension shaft 9 at the spiral groove, and by the engagement therewith will cause the shaft 9 to turn or rotate, and accordingly the shaft 8 to turn or rotate and thereby 55 start the engine. After the engine has been started as described, the rod 41 may be returned or moved to such position as to cause the several parts described to operate, to remove the shafts 12 from projection into or 60 engagement with the groove 10.

It may be stated that the device is of such form that the same may be located on either end of the engine shaft desired, and that the same forms an attachment which may be suitably connected up or fastened to the

main shaft of an engine without necessitating alteration of any parts thereof.

As only the preferred embodiment of my invention has been illustrated and described, it is to be understood that changes therein 70 may be made provided the same fall within the spirit and scope of the appended claims.

Having thus described my said invention, what I claim and desire to secure by Letters Patent is:—

1. In an engine starting device, a slidable body, shaft means to impart motion to the engine, said shaft means extending through said body and being provided with a groove, means to slide said body, a movable member on said body movable into and out of said groove, and means to positively actuate said movable member operable manually independently of said means to slide the body. 80

2. In an engine starting device, a movable body, shaft means to impart motion to the engine, said shaft means extending through said body and being provided with a groove, means on said body extending into said groove, track rails, wings on said body engaging said track rails, actuating means for the second mentioned means having parts exterior of the body, frame means to which said parts are connected, said frame means comprising a plurality of sections, one section 90 being located on each of the opposite sides of the wings, and means to secure said sections to said wings. 95

3. In an engine starting device, a body, shaft means to impart motion to the engine, said shaft means extending through said body and being provided with a groove, a laterally extending cross-head, means on said body on which said cross-head slides longitudinally of the shaft means, means for 100 actuating said cross-head, said body being provided with means engaging said groove, and means operable through movement of said cross-head and independently of movement of the body to positively move said means projecting into said groove, into or out of the groove. 105

4. In an engine starting device, a body, means to slide said body, shaft means to impart motion to the engine, said means extending through the body and provided with a groove, a shaft on said body movable into said groove, and means operable manually independently of said first means to 115 positively shift said shaft into and out of engagement with said groove. 120

5. In an engine starting device, a body, means to slide said body, shaft means to impart motion to the engine, said means extending through said body and provided with a groove, a shaft having screw threaded engagement with said body having one end extending into said groove, and turnable means operable manually independently of said first means to positively shift said shaft 130

into and out of engagement with said groove.

6. In an engine starting device, a body, shaft means to impart motion to the engine, said means extending therethrough and provided with a groove, a projecting member movable to engage and disengage said groove, a movable member, means to positively actuate said movable member independently of movement of the body, and means to move said projecting member into and out of engagement with the groove through movement of said movable member.

7. In an engine starting device, a body, shaft means to impart motion to the engine, said means extending therethrough and provided with a groove, a shaft extending into said groove having screw threaded engagement with said body, a gear wheel on said shaft, a second shaft, a gear wheel on said second shaft in mesh with said gear wheel, and means to actuate said second shaft.

8. In an engine starting device, a body, shaft means to impart motion to the engine, said means extending therethrough and provided with a groove, a shaft extending into said groove, a gear wheel on said shaft, a second shaft, a gear wheel thereon in mesh with the said gear wheel, both of said shafts having screw threaded engagement with said body, and means to actuate said second shaft.

9. In an engine starting device, a slidable body, shaft means to impart motion to the engine, said means extending therethrough and provided with a groove, a shaft extending into said groove having screw threaded engagement with said body, said shaft provided with a gear wheel thereon, a second shaft, a gear wheel on said second shaft in mesh with said gear wheel, a crank arm on said second shaft, a rotatable operating rod device having a crank arm, and connecting means between said crank arm of the rod and the crank arm of the second shaft.

10. In an engine starting device, a slid- able body, shaft means to impart motion to the engine, said means extending therethrough and provided with a groove, a shaft on said body extending into said groove, said shaft having screw threaded engagement with said body, a gear wheel on said shaft, a second shaft, a gear wheel on said second shaft in mesh with said gear wheel, a crank arm on said second shaft, a pitman connected to said crank arm, a cross-head, and means to slide said cross-head.

11. In an engine starting device, a slid- able body, shaft means to impart motion to the engine, said means extending therethrough and provided with a groove, a shaft on said body having screw threaded engagement therewith and projecting into said groove, a gear wheel on said shaft, a

second shaft, a gear wheel on said second shaft in mesh with the said gear wheel, a cross-head, a guide rod therefor provided on the body, a crank arm on said second shaft, and a pitman pivoted to said crank arm and to said cross-head, and means to slide said cross-head.

12. In an engine starting device, a slid- able body, shaft means to impart motion to the engine, said means extending therethrough and provided with a groove, a shaft having screw threaded engagement with said body extending into said groove, a gear wheel on said shaft, a second shaft on said body, a gear wheel on said second shaft in mesh with the said gear wheel, a crank arm on said second shaft, a rod projecting from said body, a cross-head slid- able on said rod, a pitman pivoted to said cross-head and to said crank arm, a yoke pivoted to said cross-head, said rod having a stop arm beyond said cross-head, and means to slide said cross-head having connection with said yoke.

13. In an engine starting device, a body, shaft means to impart motion to the engine, said means extending therethrough and provided with a groove, a shaft having screw threaded engagement with said body extending into said groove, a gear wheel on said shaft, a second shaft, a gear wheel on said second shaft in mesh with said gear wheel, a crank arm, an operating rod, locking means for said rod, said rod provided with a crank arm, and connecting means between said crank arm of the rod and said crank arm of the second shaft.

14. In an engine starting device, a body, shaft means to impart motion to the engine, said means extending therethrough and provided with a groove, shafts on said body having screw threaded engagement therewith, each of said shafts having a gear wheel thereon, second shafts, gear wheels on said second shafts in mesh with said gear wheels, crank arms on said second shafts, a cross-head, pitmen on said cross-head connected to said crank arms, guide means for said cross-head, a yoke connected to said cross-head, a rod connected to said yoke, a link, and an operating rod having a crank arm connected to said link.

15. In an engine starting device, a body, track rails on which said body moves, means to slide said body comprising a rod connected thereto, a link connected to said rod, and an operating lever connected to said link; shaft means to impart motion to the engine, said means extending through said body and provided with a spiral groove, frames connected to said body, shafts journaled in said frames having screw threaded engagement with said body and extending into said groove, gear wheels on said shafts, second shafts journaled in said frames and

extending into said body, gear wheels on said second shafts in mesh with said gear wheels, crank arms on said second shafts, a guide rod connected to said body, a cross-head slidable on said guide rod, pitmen pivoted to said cross-head and to said crank arms, an operating member, means to support said member from said operating lever, means to secure said member in adjusted po-

sition, said member having a crank arm, a link pivoted thereto, and means pivoted to said cross-head connecting said link and cross-head.
